CONTROL CIRCUIT AND DISPLAY DEVICE**CROSS REFERENCE**

This application claims the priority of Chinese Patent Application No. 201510229355.2, entitled "Control circuit and display device", filed on May 7, 2015, the disclosure of which is incorporated herein by reference in its entirety.

FIELD OF THE INVENTION

The present invention relates to an electronic technology field, and more particularly to a control circuit and a display device.

BACKGROUND OF THE INVENTION

In display devices, the connection lines are formed among the output channels of the source driver and the data lines of the pixel array for respectively coupling the output channels of the source driver with the data lines. The data signal outputted by the output channels of the source driver is transmitted from the first row to the last row of the pixel array. The connection line is longer, and the resistance of the line is larger. The voltage charge quantity of the liquid crystal units in the pixel array changes according to the resistances of the lines. The voltage charge quantity of the liquid crystal unit coupled to the data line with large line resistance is smaller than the voltage charge quantity of the liquid crystal unit coupled to the data line with relatively smaller line resistance. Because the voltage charge quantity of the liquid crystal unit varies with the change of the connection line resistance, the display image of the display device has nonuniform defects.

SUMMARY OF THE INVENTION

An objective of the present invention is to provide a control circuit and display device to enforce the uniformity of the display image of the display device.

For realizing the aforesaid objective, the technical solution provided by the embodiments of the present invention is:

The present invention provides a drive control circuit, comprising a driver, a pixel array and a resistor, and the pixel array comprises $M \times N$ pixels aligned in a form M rows $\times N$ columns, and M is a natural number larger than 1, and N is a natural number, and the driver is coupled to the N columns pixels of the pixel array through the resistor to charge the N columns pixels, and the resistor comprises a first resistor and a second resistor, and a resistance of the first resistor is larger than a resistance of the second resistor, and an area surrounded by the pixel array is divided into a first area and a second area, and both the first area and the second area comprise at least one row pixels, and a length of a connection line of the driver with any row pixels in the first area is smaller than a length of a connection line of the driver with any row pixels in the second area, and when the driver determines that it is required to sequentially supply power to each row pixels of the first area, the first resistor is activated to make a power supply signal outputted by the driver pass through the first resistor and be sequentially outputted to each row pixels of the first area for sequentially supplying power to the each row pixels of the first area, and when the driver determines that it is required to sequentially supply power to each row pixels of the second area, the second resistor is activated to make the power supply signal outputted by the driver pass through the second resistor and be sequentially outputted to each row pixels of the second area for sequentially supplying power to the each row pixels of the second area to balance charge quantity of the each row pixels.

putted by the driver pass through the second resistor and be sequentially outputted to each row pixels of the second area for sequentially supplying power to the each row pixels of the second area to balance charge quantity of the each row pixels.

The pixel array further comprises $R \times N$ pixels aligned in a form R rows $\times N$ columns, and the $R \times N$ pixels are aligned under the $M \times N$ pixels to construct a pixel array of $M+R$ rows $\times N$ columns, and the $R \times N$ pixels surround a third area, and R is a natural number larger than 1, and a length of a connection line of the driver with any row pixels in the third area is larger than the length of the connection line of the driver with any row pixels in the second area, and the resistor further comprises a third resistor, and a resistance of the third resistor is smaller than the resistance of the second resistor, and when the driver determines that it is required to sequentially supply power to each row pixels of the third area, the third resistor is activated to make the power supply signal outputted by the driver pass through the third resistor and be sequentially outputted to each row pixels of the third area for sequentially supplying power to the each row pixels of the third area to balance charge quantity of the each row pixels in the pixel array of $(M+R)$ rows $\times N$ columns.

A length in the first area of the lines of the driver coupling to the first to the $M+R$ th row pixels through the resistors is equal to a length in the second area of the lines of the driver coupling to the first to the $M+R$ th row pixels through the resistors and a length in the third area of the lines of the driver coupling to the first to the $M+R$ th row pixels through the resistors.

An amount of the resistor is one.

An amount of the resistors is N , and each column pixels are coupled to the driver through one resistor, and the resistances of the first resistors in the N resistors are equal, and the resistances of the second resistors in the N resistors are equal, and the resistances of the third resistors in the N resistors are equal.

All the resistances of the first resistors, the second resistors and the third resistors in the N resistors are gradually increased from the first column and the N th column respectively to a middle position.

The N columns pixels are symmetric with the pixel array of $(M+R)$ rows $\times N$ columns being a central line, and two first resistors coupled with two columns pixels which are mutually symmetric are equal, and two second resistors coupled with the two columns pixels which are mutually symmetric are equal, and two third resistors coupled with the two columns pixels which are mutually symmetric are equal.

The present invention further provides a display device, comprising a driver, a display panel, a pixel array and a resistor, and the pixel array comprises $M \times N$ pixels aligned in a form M rows $\times N$ columns, and M is a natural number larger than 1, and N is a natural number, and the driver is coupled to the N columns pixels of the pixel array through the resistor to charge the N columns pixels, and the resistor comprises a first resistor and a second resistor, and a resistance of the first resistor is larger than a resistance of the second resistor, and an area surrounded by the pixel array is divided into a first area and a second area, and both the first area and the second area comprise at least one row pixels, and a length of a connection line of the driver with any row pixels in the first area is smaller than a length of a connection line of the driver with any row pixels in the second area, and when the driver determines that it is required to sequentially supply power to each row pixels of the first area, the first resistor is activated to make a power supply signal outputted by the driver pass through the first resistor and be sequentially outputted to each row pixels of the first area for sequentially supplying power to the each row pixels of the first area to balance charge quantity of the each row pixels.

tially outputted to each row pixels of the first area for sequentially supplying power to the each row pixels of the first area, and when the driver determines that it is required to sequentially supply power to each row pixels of the second area, the second resistor is activated to make the power supply signal outputted by the driver pass through the second resistor and be sequentially outputted to each row pixels of the second area for sequentially supplying power to the each row pixels of the second area to balance charge quantity of the each row pixels.

The pixel array further comprises $R \times N$ pixels aligned in a form R rows $\times N$ columns, and the $R \times N$ pixels are aligned under the $M \times N$ pixels to construct a pixel array of $M+R$ rows $\times N$ columns, and the $R \times N$ pixels surround a third area, and R is a natural number larger than 1, and a length of a connection line of the driver with any row pixels in the third area is larger than the length of the connection line of the driver with any row pixels in the second area, and the resistor further comprises a third resistor, and a resistance of the third resistor is smaller than the resistance of the second resistor, and when the driver determines that it is required to sequentially supply power to each row pixels of the third area, the third resistor is activated to make the power supply signal outputted by the driver pass through the third resistor and be sequentially outputted to each row pixels of the third area for sequentially supplying power to the each row pixels of the third area to balance charge quantity of the each row pixels in the pixel array of $(M+R)$ rows $\times N$ columns.

A length in the first area of the lines of the driver coupling to the first to the $M+R$ th row pixels through the resistors is equal to a length in the second area of the lines of the driver coupling to the first to the $M+R$ th row pixels through the resistors and a length in the third area of the lines of the driver coupling to the first to the $M+R$ th row pixels through the resistors.

An amount of the resistor is one.

An amount of the resistors is N , and each column pixels are coupled to the driver through one resistor, and the resistances of the first resistors in the N resistors are equal, and the resistances of the second resistors in the N resistors are equal, and the resistances of the third resistors in the N resistors are equal.

All the resistances of the first resistors, the second resistors and the third resistors in the N resistors are gradually increased from the first column and the N th column respectively to a middle position.

The N columns pixels are symmetric with the pixel array of $(M+R)$ rows $\times N$ columns being a central line, and two first resistors coupled with two columns pixels which are mutually symmetric are equal, and two second resistors coupled with the two columns pixels which are mutually symmetric are equal, and two third resistors coupled with the two columns pixels which are mutually symmetric are equal.

The driver of the present invention needs to charge each row pixels of the pixel array. Because the pixel array comprises a plurality of rows of pixels, the plurality of rows of pixels are sequentially aligned in a form of array to be arranged under the driver. The distances of the different rows of pixels with the driver are different. The lengths of the connection lines of the driver with each row pixels are different. Meanwhile, with the distance between the row of the pixels and the driver gets larger and larger, the length of the connection line of the driver with the corresponding row of the pixels also gets longer and longer. The longer the connection is, the larger the connection resistance is, too. Thus, the charging quantity of the driver to the corresponding row of pixels is smaller. Consequently, the charge

quantity to the entire pixel array is not even. The display brightness of the entire pixel array becomes uneven. The drive control circuit of the present invention comprises a resistor. The driver is coupled to the N columns pixels of the pixel array through the resistor to charge the N columns pixels. The resistor comprises a first resistor and a second resistor. An area surrounded by the pixel array is divided into a first area and a second area. Both the first area and the second area comprise at least one row pixels. A length of a connection line of the driver with any row pixels in the first area is smaller than a length of a connection line of the driver with any row pixels in the second area. When the driver determines that it is required to sequentially supply power to each row pixels of the first area, the first resistor is activated to make a power supply signal outputted by the driver pass through the first resistor and be sequentially outputted to each row pixels of the first area for sequentially supplying power to the each row pixels of the first area. When the driver determines that it is required to sequentially supply power to each row pixels of the second area, the second resistor is activated to make the power supply signal outputted by the driver pass through the second resistor and be sequentially outputted to each row pixels of the second area for sequentially supplying power to the each row pixels of the second area. Because the resistance of the first resistor is larger than the resistance of the second resistor, the first total resistance (a sum of the corresponding line resistance and the first resistor) of the lines of the driver with the pixels in the first area and the second total resistance (a sum of the corresponding line resistance and the second resistor) of the lines of the driver with the pixels in the second area are balanced. Thus, the charge quantity of the driver to the corresponding row pixels is balanced. Therefore, the display brightness of the entire pixel array is balanced.

BRIEF DESCRIPTION OF THE DRAWINGS

In order to more clearly illustrate the embodiments of the present invention, the following figures will be described in the embodiments are briefly introduced. It is obvious that the drawings are only some embodiments of the present invention, those of ordinary skill in this field can obtain other figures according to these figures without paying the premise.

FIG. 1 is a block diagram of a drive control circuit provide by the first embodiment of the first solution according to the present invention;

FIG. 2 is a block diagram of a drive control circuit provide by the second embodiment of the first solution according to the present invention;

FIG. 3 is a block diagram of a display device provided by the embodiment of the second solution according to the present invention.

DETAILED DESCRIPTION OF PREFERRED EMBODIMENTS

For better explaining the technical solution and the effect of the present invention, the present invention will be further described in detail with the accompanying drawings in the specific embodiments.

Please refer to FIG. 1. The first embodiment of the first solution according to the present invention provides a drive control circuit 100. The drive control circuit 100 comprises a driver 10, a pixel array 20 and a resistor 30. The pixel array 20 comprises $M \times N$ pixels (not shown) aligned in a form M rows $\times N$ columns, wherein M is a natural number larger than

1, and N is a natural number. The driver **10** is coupled to the N columns pixels of the pixel array **20** through the resistor **30** to charge the N columns pixels. The resistor **30** comprises a first resistor R1 and a second resistor R2. A resistance of the first resistor R1 is larger than a resistance of the second resistor R2. An area surrounded by the pixel array **20** is divided into a first area **21** and a second area **22**. Both the first area **21** and the second area **22** comprise at least one row pixels. A length of a connection line of the driver **10** with any row pixels in the first area **21** is smaller than a length of a connection line of the driver **10** with any row pixels in the second area **22**. When the driver **10** determines that it is required to sequentially supply power to each row pixels of the first area, the first resistor R1 is activated to make a power supply signal outputted by the driver **10** pass through the first resistor R1 and be sequentially outputted to each row pixels of the first area **21** for sequentially supplying power to the each row pixels of the first area **21**. When the driver **10** determines that it is required to sequentially supply power to each row pixels of the second area **22**, the second resistor R2 is activated to make the power supply signal pass through the second resistor R2 and be sequentially outputted to each row pixels of the second area **22** for sequentially supplying power to the each row pixels of the second area **22** to balance charge quantity of the each row pixels.

Specifically, a first predetermined interval and a second predetermined interval are recorded in the driver **10**, wherein the second predetermined interval is equal to the first predetermined interval multiply by row number of the pixels in the first area **21**. After the display device is powered on, the driver **10** determines that it is required to charge a plurality of rows of pixels in the first area **21**. First, the driver **10** automatically charges the first row pixels in the first area **21** through the first resistor R1, and times. After reaching the first predetermined interval, the second row pixels in the first area **21** is charged simultaneously right after the charge to the first row pixels in the first area **21** is stopped, and so on. In every first predetermined interval, the next row pixels are charged right after the charge to the present row pixel is stopped. After the last row pixels in the first area **21** are charged in the first predetermined interval, then, the driver **10** recognizes that the second predetermined interval is reached. The driver **10** determines that it is required to charge a plurality of rows of pixels in the second area **22**. The driver **10** activates the second resistor R2 and charges the plurality of rows of pixels in the second area **22** through the second resistor R2, and times. After reaching the first predetermined interval, the second row pixels in the second area **22** is charged simultaneously right after the charge to the first row pixels in the second area **22** is stopped, and so on. In every first predetermined interval, the next row pixels are charged right after the charge to the present row pixel is stopped. After the last row pixels in the second area **22** are charged in the first predetermined interval, one charge cycle to the pixel array **20** is accomplished.

In this embodiment, an amount of the resistor **30** is one. The first resistor R1 and the second resistor R2 are connected in parallel.

The driver **10** is required to charge each row pixels of the pixel array **20**. Because the pixel array **20** comprises a plurality of rows of pixels. The plurality of rows of pixels are sequentially aligned in a form of array to be arranged under the driver **10**. The distances of the different rows of pixels with the driver **10** are different. The lengths of the connection lines of the driver **10** with each row pixels are different. Meanwhile, with the distance between the row of the pixels and the driver **10** gets larger and larger, the length of the

connection line of the driver **10** with the corresponding row of the pixels also gets longer and longer. The longer the connection is, the larger the connection resistance is, too. Thus, the charging quantity of the driver **10** to the corresponding row of pixels is smaller. Consequently, the charge quantity to the entire pixel array **20** is not even. The display brightness of the entire pixel array **20** becomes uneven. In this embodiment, the drive control circuit **100** comprises a resistor **30**. The driver **10** is coupled to the N columns pixels of the pixel array **20** through the resistor **30** to charge the N columns pixels. The resistor **30** comprises a first resistor R1 and a second resistor R2. An area surrounded by the pixel array **20** is divided into a first area **21** and a second area **22**. Both the first area **21** and the second area **22** comprise at least one row pixels. A length of a connection line of the driver **10** with any row pixels in the first area **21** is smaller than a length of a connection line of the driver **10** with any row pixels in the second area **22**. When the driver **10** determines that it is required to sequentially supply power to each row pixels of the first area, the first resistor R1 is activated to make a power supply signal outputted by the driver **10** pass through the first resistor R1 and be sequentially outputted to each row pixels of the first area **21** for sequentially supplying power to the each row pixels of the first area **21**. When the driver **10** determines that it is required to sequentially supply power to each row pixels of the second area **22**, the second resistor R2 is activated to make the power supply signal pass through the second resistor R2 and be sequentially outputted to each row pixels of the second area **22** for sequentially supplying power to the each row pixels of the second area **22**. Because the resistance of the first resistor R1 is larger than the resistance of the second resistor R2, the first total resistance (a sum of the corresponding line resistance and the first resistor) of the lines of the driver **10** with the pixels in the first area **21** and the second total resistance (a sum of the corresponding line resistance and the second resistor) of the lines of the driver **10** with the pixels in the second area **22** are balanced. Thus, the charge quantity of the driver **10** to the corresponding row pixels is balanced. Therefore, the display brightness of the entire pixel array **20** is balanced.

Please refer to FIG. 2. The second embodiment of the present invention provides a drive control circuit **200**. The drive control circuit **200** provided by the second embodiment is similar with the drive control circuit **100** provided by the first embodiment. The difference between the two is: in the second embodiment, the pixel array **210** further comprises R×N pixels aligned in a form R rows×N columns. The R×N pixels are aligned under the M×N pixels to construct a pixel array of M+R rows×N columns. The R×N pixels surround a third area **23**, wherein R is a natural number larger than 1. A length of a connection line of the driver **10** with any row pixels in the third area **23** is larger than a length of a connection line of the driver **10** with any row pixels in the second area **22**. The resistor **220** further comprises a third resistor R3. A resistance of the third resistor R3 is smaller than the resistance of the second resistor R2, and when the driver **10** determines that it is required to sequentially supply power to each row pixels of the third area **23**, the third resistor R3 is activated to make the power supply signal outputted by the driver **10** pass through the third resistor R3 and be sequentially outputted to each row pixels of the third area for sequentially supplying power to the each row pixels of the third area **23** to balance charge quantity of the each row pixels in the pixel array **210** of (M+R) rows×N columns.

Specifically, a third predetermined interval is recorded in the driver **10**, wherein the third predetermined interval is

equal to the first predetermined interval multiply by row number of the pixels in the second area **22**. After the last row pixels in the second area **22** are charged in the first predetermined interval, then, the driver **10** recognizes that the third predetermined interval is reached. The driver **10** determines that it is required to charge a plurality of rows of pixels in the third area **23**. The driver **10** activates the third resistor **R3**, and charges the first row pixels in the third area **23** through the third resistor **R3**, and times. After reaching the first predetermined interval, the second row pixels in the third area **23** is charged simultaneously right after the charge to the first row pixels in the third area **23** is stopped, and so on. In every first predetermined interval, the next row pixels are charged right after the charge to the present row pixel is stopped. After the last row pixels in the third area **23** are charged in the first predetermined interval, one charge cycle to the pixel array **210** is accomplished.

The first resistor **R1**, the second resistor **R2** and the third resistor **R3** in each resistor **220** are connected in parallel.

In this embodiment, the driver **10** is required to charge each row pixels of the pixel array **210**. Because the pixel array **210** comprises a plurality of rows of pixels, the plurality of rows of pixels are sequentially aligned in a form of array to be arranged under the driver **10**. The distances of the different rows of pixels with the driver **10** are different. The lengths of the connection lines of the driver **10** with each row pixels are different. Meanwhile, with the distance between the row of the pixels and the driver **10** gets larger and larger, the length of the connection line of the driver **10** with the corresponding row of the pixels also gets longer and longer. The longer the connection is, the larger the connection resistance is, too. Thus, the charging quantity of the driver **10** to the corresponding row of pixels is smaller. Consequently, the charge quantity to the entire pixel array **20** is not even. The display brightness of the entire pixel array **20** becomes uneven. In this embodiment, the drive control circuit **100** comprises a resistor **30**. The driver **10** is coupled to the N columns pixels of the pixel array **210** through the resistor **30** to charge the N columns pixels. The resistor **30** comprises a first resistor **R1**, a second resistor **R2** and a third resistor **R3**. An area surrounded by the pixel array **20** is divided into a first area **21**, a second area **22** and a third area **23**. A length of a connection line of the driver **10** with any row pixels in the first area **21** is smaller than a length of a connection line of the driver **10** with any row pixels in the second area **22**. A length of a connection line of the driver **10** with any row pixels in the second area **22** is smaller than a length of a connection line of the driver **10** with any row pixels in the third area **23**. When the driver **10** determines that it is required to sequentially supply power to each row pixels of the first area, the first resistor **R1** is activated to make a power supply signal outputted by the driver **10** pass through the first resistor **R1** and be sequentially outputted to each row pixels of the first area **21** for sequentially supplying power to the each row pixels of the first area **21**. When the driver **10** determines that it is required to sequentially supply power to each row pixels of the second area **22**, the second resistor **R2** is activated to make the power supply signal pass through the second resistor **R2** and be sequentially outputted to each row pixels of the second area **22** for sequentially supplying power to the each row pixels of the second area **22**. When the driver **10** determines that it is required to sequentially supply power to each row pixels of the third area **23**, the third resistor **R3** is activated to make the power supply signal pass through the third resistor **R3** and be sequentially outputted to each row pixels of the third area **23** for sequentially supplying power to the each row pixels of

the third area **23**. Because the resistance of the first resistor **R1** is larger than the resistance of the second resistor **R2** and the resistance of the second resistor **R2** is larger than the resistance of the third resistor **R3**, the first total resistance (a sum of the corresponding line resistance and the first resistor **R1**) of the lines of the driver **10** with the pixels in the first area **21** and the second total resistance (a sum of the corresponding line resistance and the second resistor **R2**) of the lines of the driver **10** with the pixels in the second area **22**, the third total resistance (a sum of the corresponding line resistance and the third resistor **R3**) of the lines of the driver **10** with the pixels in the third area **23** are balanced. Thus, the charge quantity of the driver **10** to the pixels of the pixel array **210** is balanced. Therefore, the display brightness of the entire pixel array **210** is balanced.

Furthermore, a length in the first area **21** of the lines of the driver **10** coupling to the first to the $M+R_{th}$ row pixels through the resistors **220** is equal to a length in the second area **22** of the lines of the driver **10** coupling to the first to the $M+R_{th}$ row pixels through the resistors **220** and a length in the third area **23** of the lines of the driver **10** coupling to the first to the $M+R_{th}$ row pixels through the resistors **220**.

In this embodiment, an amount of the resistors **220** is N . Each column pixels are coupled to the driver **10** through one resistor **220**, and the resistances of the first resistors **R1** in the N resistors **220** are equal. The resistances of the second resistors **R2** in the N resistors **220** are equal. The resistances of the third resistors **R3** in the N resistors **220** are equal.

Furthermore, all the resistances of the first resistors **R1**, the second resistors **R2** and the third resistors **R3** in the N resistors **230** are gradually increased from the first column and the N th column respectively to a middle position.

Specifically, as considering the length condition of the connection lines of the driver **10** coupling to the first row pixels of the pixel array **210**: the lengths of the lines are gradually decreased from the first column and the N th column respectively to a middle position. Therefore, all the resistances of the first resistors **R1**, the second resistors **R2** and the third resistors **R3** in the N resistors **230** are gradually increased from the first column and the N th column respectively to a middle position to balance the total resistance of the lines of the driver coupling to the respective row pixels of the pixel array **210** for balancing the charge quantity of the driver **10** to the pixels of the pixel array **210**. Therefore, the display brightness of the entire pixel array **210** is balanced.

Specifically, the N columns pixels are symmetric with the pixel array **210** of $(M+R) \times N$ columns being a central line, and two first resistors **R1** coupled with two columns pixels which are mutually symmetric are equal; two second resistors **R2** coupled with the two columns pixels which are mutually symmetric are equal; two third resistors **R3** coupled with the two columns pixels which are mutually symmetric are equal.

Please refer to FIG. 3, a display device **300** provided by the second solution according to the present invention. The display device **300** comprises a display panel **310** and a drive control circuit. The drive control circuit can be the drive control circuit **100** provided by the first embodiment of the first solution or the drive control circuit **200** provided by the second embodiment. In this embodiment, the drive control circuit is the drive control circuit **200** provided by the second embodiment of the first solution. The pixel array **210** of the drive control circuit **200** is located on the display panel **310**. The specific structure and function of the drive control

circuit 200 have already been described in detail in the aforesaid first solution. The repeated description is omitted here.

In this embodiment, the driver 10 is required to charge each row pixels of the pixel array 210. Because the pixel array 20 comprises a plurality of rows of pixels, the plurality of rows of pixels are sequentially aligned in a form of array to be arranged under the driver 10. The distances of the different rows of pixels with the driver 10 are different. The lengths of the connection lines of the driver 10 with each row pixels are different. Meanwhile, with the distance between the row of the pixels and the driver 10 gets larger and larger, the length of the connection line of the driver 10 with the corresponding row of the pixels also gets longer and longer. The longer the connection is, the larger the connection resistance is, too. Thus, the charging quantity of the driver 10 to the corresponding row of pixels is smaller. Consequently, the charge quantity to the entire pixel array 210 is not even. The display brightness of the entire pixel array 210 becomes uneven. In this embodiment, the drive control circuit 200 comprises a resistor 220. The driver 10 is coupled to the N columns pixels of the pixel array 210 through the resistor 220 to charge the N columns pixels. The resistor 220 comprises a first resistor R1, a second resistor R2 and a third resistor R3. An area surrounded by the pixel array 20 is divided into first to third areas 21-23. All the first area 21 to the third area 23 comprise at least one row pixels. A length of a connection line of the driver 10 with any row pixels in the first area 21 is smaller than a length of a connection line of the driver 10 with any row pixels in the second area 22. A length of a connection line of the driver 10 with any row pixels in the second area 22 is smaller than a length of a connection line of the driver 10 with any row pixels in the third area 23. When the driver 10 determines that it is required to sequentially supply power to each row pixels of the first area 21, the first resistor R1 is activated to make a power supply signal outputted by the driver 10 pass through the first resistor R1 and be sequentially outputted to each row pixels of the first area 21 for sequentially supplying power to the each row pixels of the first area 21. when the driver 10 determines that it is required to sequentially supply power to each row pixels of the second area 22, the second resistor R2 is activated to make the power supply signal pass through the second resistor R2 and be sequentially outputted to each row pixels of the second area 22 for sequentially supplying power to the each row pixels of the second area 22. when the driver 10 determines that it is required to sequentially supply power to each row pixels of the third area 23, the third resistor R3 is activated to make the power supply signal pass through the third resistor R3 and be sequentially outputted to each row pixels of the third area 23 for sequentially supplying power to the each row pixels of the third area 23. Because the resistance of the first resistor R1 is larger than the resistance of the second resistor R2 and the resistance of the second resistor R2 is larger than the resistance of the third resistor R3, the first total resistance (a sum of the corresponding line resistance and the first resistor R1) of the lines of the driver 10 with the pixels in the first area 21 and the second total resistance (a sum of the corresponding line resistance and the second resistor R2) of the lines of the driver 10 with the pixels in the second area 22, the third total resistance (a sum of the corresponding line resistance and the third resistor R3) of the lines of the driver 10 with the pixels in the third area 23 are balanced. Thus, the charge quantity of the driver 10 to the corresponding row pixels is balanced. Therefore, the display brightness of the display device 300 is balanced.

Above are only specific embodiments of the present invention, the scope of the present invention is not limited to this, and to any persons who are skilled in the art, change or replacement which is easily derived should be covered by the protected scope of the invention. Thus, the protected scope of the invention should go by the subject claims.

What is claimed is:

1. A drive control circuit, comprising a single data driver, 10 a pixel array and at least one first resistor and at least one second resistor, and the pixel array comprises $M \times N$ pixels aligned in a form M rows $\times N$ columns, and M is a natural number larger than 1, and N is a natural number, and the single data driver is coupled to the N columns pixels of the 15 pixel array through the at least one first resistor and the at least one second resistor to charge the N columns pixels, wherein the at least one first resistor and the at least one second resistor are coupled in parallel between the single data driver and one column pixels and a resistance of the first 20 resistor is larger than a resistance of the second resistor, and an area surrounded by the pixel array is divided into a first area and a second area, and both the first area and the second area comprise at least one row pixels, and a length of a connection line of the single data driver with any row pixels 25 in the first area is smaller than a length of a connection line of the single data driver with any row pixels in the second area, and when the single data driver determines that it is required to sequentially supply power to each row pixels of the first area, the first resistor is selected and activated by the 30 single data driver to make a power supply signal outputted by the single data driver pass through the first resistor and be sequentially outputted to each row pixels of the first area for sequentially supplying power to the each row pixels of the first area, and when the single data driver determines that it is required to sequentially supply power to each row pixels of the second area, the second resistor is selected and activated by the single data driver to make the power supply signal outputted by the single data driver pass through the second resistor and be sequentially outputted to each row 35 pixels of the second area for sequentially supplying power to the each row pixels of the second area to balance charge quantity of the each row pixels.

2. The drive control circuit according to claim 1, wherein 45 the pixel array further comprises $R \times N$ pixels aligned in a form R rows $\times N$ columns, and the $R \times N$ pixels are aligned under the $M \times N$ pixels to construct a pixel array of $M+R$ rows $\times N$ columns, and the $R \times N$ pixels surround a third area, and R is a natural number larger than 1, and a length of a connection line of the single data driver with any row pixels 50 in the third area is larger than the length of the connection line of the single data driver with any row pixels in the second area, and the drive control circuit further comprises at least one third resistor, and the single data driver is coupled to the N columns pixels of the pixel array through the at least one first resistor, the at least one second resistor and the at least one third resistor to charge the N columns pixels, wherein the at least one first resistor, the at least one second resistor and the at least one third resistor are coupled in parallel between the single data driver and the one column 55 pixels, and a resistance of the third resistor is smaller than the resistance of the second resistor, and when the single data driver determines that it is required to sequentially supply power to each row pixels of the third area, the third resistor is activated to make the power supply signal outputted by the single data driver pass through the third resistor and be sequentially outputted to each row pixels of the third area for sequentially supplying power to the each 60

11

row pixels of the third area to balance charge quantity of the each row pixels in the pixel array of $(M+R)$ rows×N columns.

3. The drive control circuit according to claim 2, wherein a length in the first area of lines of the single data driver coupling to the first to the $M+R$ th row pixels through the resistors is equal to a length in the second area of lines of the single data driver coupling to the first to the $M+R$ th row pixels through the resistors and a length in the third area of line of the single data driver coupling to the first to the $M+R$ th row pixels through the resistors.

4. The drive control circuit according to claim 3, wherein the resistances of the first resistors are equal, and the resistances of the second resistors are equal, and the resistances of the third resistors are equal.

5. The drive control circuit according to claim 4, wherein all the resistances of the first resistors, the second resistors and the third resistors in the N resistors are gradually increased from the first column and the Nth column respectively to a middle position.

6. The drive control circuit according to claim 5, wherein the N columns pixels are symmetric with the pixel array of $(M+R)$ rows×N columns being a central line, and two first resistors coupled with two columns pixels which are mutually symmetric are equal, and two second resistors coupled with the two columns pixels which are mutually symmetric are equal, and two third resistors coupled with the two columns pixels which are mutually symmetric are equal.

7. A display device, comprising a single data driver, a display panel, a pixel array and at least one first resistor and at least one second resistor, and the pixel array comprises $M \times N$ pixels aligned in a form M rows× N columns, and M is a natural number larger than 1, and N is a natural number, and the single data driver is coupled to the N columns pixels of the pixel array through the at least one first resistor and the at least one second resistor to charge the N columns pixels, wherein the at least one first resistor and the at least one second resistor are coupled in parallel between the single data driver and one column pixels and a resistance of the first resistor is larger than a resistance of the second resistor, and an area surrounded by the pixel array is divided into a first area and a second area, and both the first area and the second area comprise at least one row pixels, and a length of a connection line of the single data driver with any row pixels in the first area is smaller than a length of a connection line of the single data driver with any row pixels in the second area, and when the single data driver determines that it is required to sequentially supply power to each row pixels of the first area, the first resistor is selected and activated by the single data driver to make a power supply

12

signal outputted by the single data driver pass through the first resistor and be sequentially outputted to each row pixels of the first area for sequentially supplying power to the each row pixels of the first area, and when the single data driver determines that it is required to sequentially supply power to each row pixels of the second area, the second resistor is selected and activated by the single data driver to make the power supply signal outputted by the single data driver pass through the second resistor and be sequentially outputted to each row pixels of the second area for sequentially supplying power to the each row pixels of the second area to balance charge quantity of the each row pixels.

8. The display device according to claim 7, wherein the pixel array further comprises $R \times N$ pixels aligned in a form R rows× N columns, and the $R \times N$ pixels are aligned under the $M \times N$ pixels to construct a pixel array of $M+R$ rows× N columns, and the $R \times N$ pixels surround a third area, and R is a natural number larger than 1, and a length of a connection line of the single data driver with any row pixels in the third area is larger than the length of the connection line of the single data driver with any row pixels in the second area, and the display device further comprises at least one third resistor, and the single data driver is coupled to the N columns pixels of the pixel array through the at least one first resistor, the at least one second resistor and the at least one third resistor to charge the N columns pixels, wherein the at least one first resistor, the at least one second resistor and the at least one third resistor are coupled in parallel between the single data driver and the one column pixels, and a resistance of the third resistor is smaller than the resistance of the second resistor, and when the single data driver determines that it is required to sequentially supply power to each row pixels of the third area, the third resistor is selected and activated by the single data driver to make the power supply signal outputted by the single data driver pass through the third resistor and be sequentially outputted to each row pixels of the third area for sequentially supplying power to the each row pixels of the third area to balance charge quantity of the each row pixels in the pixel array of $(M+R)$ rows× N columns.

9. The display device according to claim 8, wherein a length in the first area of lines of the single data driver coupling to the first to the $M+R$ th row pixels through the resistors is equal to a length in the second area of lines of the single data driver coupling to the first to the $M+R$ th row pixels through the resistors and a length in the third area of line of the single data driver coupling to the first to the $M+R$ th row pixels through the resistors.
